(57) **CLAIM**

The ornamental design for a nail drill housing, as shown and described.

DESCRIPTION

FIG. 1 is a front view of a nail drill housing showing my new design;
FIG. 2 is a left side view thereof;
FIG. 3 is a right side view thereof;
FIG. 4 is a back side view thereof;
FIG. 5 is a top view thereof; and,
FIG. 6 is a bottom view thereof.

The broken lines in the figures are for the purpose of illustrating portions of the nail drill housing, which form no part of the claimed design.

1 Claim, 2 Drawing Sheets
